UNITED STATES PATENT OFFICE

2,188,061

ELECTRIC DISCHARGE VESSEL

Rudolf Scharfnagel, Stuttgart, Germany, assignor to C. Lorenz Aktiengesellschaft, Berlin-Tempelhof, Lorenzweg, Germany, a company

Application May 13, 1938, Serial No. 207,756
In Germany May 14, 1937

7 Claims. (Cl. 250—27.5)

The invention relates to electric discharge vessels of the kind in which a disc-shaped member of ceramic or similar material is united with the bulb of the vessel by a glass seal arranged as a coating on such ceramic member, this member and seal forming a cover for the bulb. Preferably, such cover is used also to support the electrode system.

It has been customary to apply the glass intended to form this seal to both the ceramic member and bulb at the same time. Also it has been proposed to apply this glass to an insulating member, preferably of ceramic material, and simultaneously to apply it to an annular metal member arranged to encircle such insulating member, and then to unite this metal member with the bulb.

In accordance with the invention a cover of the said kind comprises a ceramic member and a glass body moulded on this member, the two thus being firmly secured together. This cover is fastened to the bulb by means of the glass body. In this way the formation of strains in the glass seal and hence cracks therein are more effectively avoided than has been possible heretofore.

The invention is also concerned with means for producing the novel covers in mass, as will be understood from the following description, reference being had to the accompanying drawings in which:

Fig. 1 is a somewhat diagrammatic sectional view of an electron tube of the type referred to by the invention. Fig. 2 is a fragmentary sectional view showing an example of a device for manufacturing one embodiment of the novel cover. Fig. 3 is a fragmentary sectional view illustrating an example of a device for manufacturing a second embodiment thereof. Fig. 4 is a fragmentary sectional view representing a second example of devices for manufacturing covers of the type shown in Fig. 2. Fig. 5 is an alternative form of a detail of the arrangement represented in Fig. 4.

The electron tube shown in Fig. 1 by way of example comprises a bulb A, an electrode system B, leads 6 joined to this system, and a cover composed of a ceramic disc-shaped member 1 and of a glass seal 5. Bulb A may be of a metal or of a suitable glass, and has a flange b to which seal 5 is fastened. Flange b is tapering toward its edge, being intended to be here of foil thickness, or nearly so. If the bulb A is of glass, flange b and seal 5 may be united with each other by the heat of a gas jet, for instance, while

in the case of a metal bulb, preferably high frequency energy is employed for heating the bulb, thus securing flange b and seal 5 together. The latter operation may be effected by the same high frequency coil that in a well known manner serves for outgassing the bulb A.

For manufacturing the cover 1, 5 the device represented in Fig. 2 may be used. This device comprises a patrinx or die 3 and a matrix composed of the ceramic member 1 itself and of a plate-shaped part 2 of iron in which member 1 is seated. Member 1 carries the leads 6. The die 3 has bores c for the leads to pass through and is fitted with heating coils 4. Matrix 1, 2 is heated from below, as indicated by the arrows d, in order to melt glass arranged thereon. This glass may be in a preheated condition or may be poured on the matrix, thus being applied thereto in liquid condition. By means of die 3 the melted glass on matrix 1, 2 is moulded to form a pressed glass body 5 of disc shape. Part 2 is of a material to which the glass body 5 does not stick. The ceramic member 1, however, is by die 3 caused to form a firmly interlocked structure with the glass body 5. Therefore, after removal of the die this structure 1, 5 may be removed from matrix part 2 in order to be united with the bulb A of an electron tube in the manner described with reference to Fig. 1.

Member 1 may have bores e or recesses into which the material of body 5 may enter. Such bores or recesses may be dispensed with if the porosity of the ceramic material is sufficient.

In the arrangement shown in Fig. 3 the matrix 1, 2' is carried on a heating body 8 of iron provided with heating coils 7. Part 2', not able to stick to glass, is displaceable in a guide 11 so that it may be moved into the position shown in dotted lines. Die 3' is disposed in a guide 9. With part 2' in the position represented in full lines, this being the position of rest, there is a hollow space above member 1. This space is somewhat larger in diameter than die 3' and is to receive the glass from which the glass body 5 is to be produced. The softened glass is in a first moulding operation pressed by die 3' against the ceramic member or matrix part 1 and thus caused to form therewith a firmly interlocked structure in the same manner as described with reference to Fig. 2. Then matrix part 2' is raised into the dotted-line position while die 3' is still in its lower position. As a result, glass body 5 is formed with a tubular extension 12 by which it shall be fastened to the bulb of an electron tube.

In the arrangement shown in Fig. 4 that part of the matrix to which glass does not stick is in the nature of a metal chill 2" in which a glass disc 5 is placed on the ceramic member 1 in order to be united therewith by die 3". Member 1 is formed with a central tubular extension 7 located in a central bore 18 of the chill. An electric coil 17 serves to preheat the glass disc 5 and ceramic member 1 until the transformation temperature of the glass is reached, i. e., the lower limit of the destraining or release range decisive for all temperature variations. At this moment coil 17 is deenergized and a fine gas jet 16 of a burner 15 is caused to act within bore 18 upon the centre portion of member 1. In this way a glowing spot is produced in the middle of member 1 so that glass disc 5 and member 1 will be secured together in the middle at first. Bores 8 in member 1 enable the heat produced by jet 16 to act directly on the disc 5. The circumferential portion of disc 5 is protected from a harmful influence of the heat by the chill 2" being of a comparatively large volume. Air ducts 9 in the chill cause the gas jet 16 to be sufficiently fine. Bore 18 is fitted with a lining 14 of heat-proof insulating material such as asbestos or clay. The chill is mounted on a table 19 that can be raised or lowered by a suitable gearing 20 in order to adjust the distance by which member 1 is spaced from the jet 16. Die 3" has pins 13 for producing bores in the glass body 5 in accordance with corresponding bores in member 1, while providing body 5 with a glass wart around each such bore. In these bores the leads for the electrode system are fixed after the assembly or cover 1, 5 has been removed from the chill.

If mass production is concerned, die 3" is replaced by the die 3A shown in Fig. 5. Die 3A has the leads 6 arranged instead of the pins 13, Fig. 4. These leads are provided with glass collars 21. After die 3A has been lowered to press the leads 6 into the softened disc 5, member 1 having corresponding bores to such end, the heat of jet 16 at once acts to unite the leads 6 with disc 5 and member 1. Preferably, the glass from which disc 5 is made is harder than that of the collars 21. The hot assembly 1, 5, 6 is then subjected to a compressed air cooling acting from

below, whereupon the cover 1, 5, 6 may be at once removed from the chill.

In lieu of a gas burner 15 an electric heating device may be employed whose heat radiation is concentrated toward the centre portion of member 1 by means of a diaphragm.

The glass disc 5 instead of being supported by both member 1 and chill 2" may be held by member 1 alone, thus being out of contact with the chill. In the case represented, where disc 5 is lying on the chill too, it is advisable to outgas the metal from which the chill is to be made, since otherwise air bubbles may form in the disc 5.

Chill 2" is preferably of the same or approximately the same coefficient of expansion as glass body 5.

The ceramic member 1 may be previously coated with glass.

What is claimed is:

1. A cover for electric discharge vessels which comprises a ceramic member and a glass body moulded on this member to form an interlocked structure therewith.

2. A cover according to claim 1, wherein the ceramic member is of sufficient porousness for the adhesion of the glass body.

3. An electric discharge vessel having a cover that comprises a ceramic member and a glass body moulded on this member, and further having electrodes held in place by said ceramic member.

4. A cover according to claim 1, wherein the glass body is formed with an edge portion projecting beyond the ceramic member.

5. A cover according to claim 1, wherein the glass body is formed with a circumferential tubular extension.

6. An electric discharge vessel having a cover that comprises a ceramic member and a glass body moulded on this member, and further having a bulb whose wall has a part of foil thickness with which the said glass body is united.

7. A cover according to claim 1, wherein the glass is interlocked with the ceramic member by means of bores located therein.

RUDOLF SCHARFNAGEL.
